UNITED STATES PATENT OFFICE.

WILLIAM W. JACKSON, OF PHILADELPHIA, PENNSYLVANIA, ASSIGNOR TO
THE MATHER MANUFACTURING COMPANY, OF SAME PLACE.

DESIGN FOR A FONT OF PRINTING-TYPE.

SPECIFICATION forming part of Design No. 20,707, dated April 28, 1891.

Application filed April 6, 1891. Serial No. 387,884. Term of patent 7 years.

To all whom it may concern:

Be it known that I, WILLIAM W. JACKSON a citizen of the United States, residing at Philadelphia, in the county of Philadelphia and State of Pennsylvania, have invented a certain new and useful Design for a Font of Printing-Type, of which the following is a full, clear, and exact description.

My design relates to the configuration of the characters of a font of printing-type.

The leading features of the design are, first, the curled lower terminals of the capitals A, B, C, D, E, F, H, J, K, M, N, P, Q, R, S, T, and Y; second, the pointed upper terminals of the capitals H, K, N, U, V, W, and Y; third, the flat tops of capital S and lower-case s; fourth, the convex descending lines in the lower-case h, m, and n, and, fifth, the convex ascending

lines in the lower-case u and y, which line in each latter ends in a sharp point.

The accompanying drawing fully illustrates these several features of my design and renders further description unnecessary.

The words "Magnificent" and "Researches" are placed upon the drawing to illustrate the appearance of the design in composition.

What I claim is—

The design for a font of printing-type, substantially as shown and described.

In testimony whereof I have hereunto set my hand this 4th day of April, A. D. 1891.

WILLIAM W. JACKSON.
